CONTAINER END CLOSURE

James A. Hollinshead, Monroe, Mich., assignor to
 Consolidated Paper Company, Monroe, Mich.,
 a corporation of Michigan

Application October 4, 1948, Serial No. 52,651

2 Claims. (Cl. 229—5.5)

1

This invention relates to self-locking ends or closures for tubular containers, especially where in the tubular wall may respond to some radial pressure in yielding slightly.

This invention has utility when incorporated in fiberboard, cardboard and paperboard types of containers in general polygonal or approaching cylindrical form with relatively inwardly foldable end wall portions, preferably of slightly over normal radial extent for snapping into an approximate transverse plane to provide a full end closure. When this set-up is taken as of hexagon general form, symmetrical triangular scored portions are continuous with bases toward the tubular body of the container. A pair of relatively foldable lobes or sections is between the remote apices of the triangles. Upon collapsing of the end extension triangles toward the closure plane, the intermediate lobes are inward therefrom to leave the group of the triangles as the sole and complete end exposure for the container.

Referring to the drawings:

Fig. 1 is a perspective view looking at a closed end of a drum type of tubular container having an embodiment of the invention incorporated therewith and in closed position for an end thereof;

Fig. 2 is a fragmentary view thru the self-sealed end closure or top of the container of Fig. 1;

Fig. 3 is a partial side elevation of the empty collapsed unfilled drum of Fig. 1, showing the end extension as flat;

Fig. 4 is an enlarged portion of the converging scorings defining the points of the lobes at the junction between adjacent bases of the respective triangles at the region of the tubular body; and

Fig. 5 is a showing in section of volume shrinkage stages in charging a container, as with hot asphalt, with which there may be lob-embedding in promoting container end sealing and reinforcement.

For asphalt drums in the range of 100# capacity, fiberboard sheets may be blanked out, say for about 22" body length and with the similar triangle extensions wherein the perpendicular length of the triangles approximate 6 1/4" for a drum having its cylinder diameter about 13 1/8". The blank in its collapsed form, as for shipping to destination to be filled, has a flat body side 1, with parallel fold line scores 2, 3, for body side portions 4, 5, having an overlap for a stapling or seam stitching 6, parallel to the score lines 2, 3.

The drum or container body extends to an end-

less peripheral or outward score line 7, normally transverse or perpendicular to the stitching 6 and the score lines 2, 3. Additional, also outward score lines as to the collapsed drum (Fig. 3) are converging score lines 8, 9, in pairs in the end closure extension from the drum body, defining the several triangles 10 in base continuity on the scoring 7. At the stitching 6, there is from the body portion 4 a fractional triangle extension portion 11 with a 60° cut back side 12 from a tip 13 at the converging of the lines 8, 9, so that the portion 11 side 12 does not overhang the score line 9 of fractional triangle portion 14 from the side 5. Also adjacent the seam or stitching 6 of the overlap, the portion 14 has a cut back side 15 from the region of the tip 13 in such proximity that the portion 14 does not overhang the score line 8. This insures that the sheet stock in its folding at the score lines is only single ply.

At the converging tips 13 for the score lines 8, 9, of the respective triangles 10 remote from the base sides 7, are lobe end or tip portions 16 of about 60° away from a perpendicular 17 to the base 7. This makes the portions 16 as fully at right angles to the score lines 8, 9, thereby rendering any hypotenuse theretoward longer than the score line base therefor.

At the base score line 7 where there is a junction 18 of the score lines 9, 8, of the there-adjoining triangles 10, an inside not-penetrating cutting 19 provides a fold-defining direction to the junction 18 from an arched inward scoring line 20 extending perpendicular to the line 7 and thereby bisecting the region between triangle apices 13. There may be arc portions 21 from the out-limit of the line 20 connecting a portion 16 each way from the line 20, thereby completing the lobe pair 22, 23, complementary to and reversely pointed as to the line 7 from the triangles 10. The scoring 20, 19, is effective in determining each lobe 22, 23, to have its point at the junction 18. In the tubular set-up of the container body, following such with directing the triangles 10 to have their apices 13 converge, the lobes 22, 23, tend to have advance inward fold to leave exposed only the triangles 10.

The container charging or filling operation may be for a freely flowing bulk material. In 50 the event such be a hot liquid, as asphalt, tending upon cooling to shrink in its transition to a frangible solid state thru a rubbery or syrupy stage, there is a volume total lessening. For instance, as the collapsible end extension is peripherally continuous, flow charging may be out-

ward beyond the score line 7, say to a region 24 (Fig. 5). Initial cooling shrinkage may develop a central less height region 25, with a marginal less-settling more or less heavy rim portion 26. A later stage may be toward a nearly fully settled region 27. While the substance be not set to resist the firm cutting thrust of lobe pair 22, 23, at inwardly extending close fold at the score 19, 20, definite stiff edge 28 may be moved into embedding coaction 29 (Fig. 2). While this performance may be carried on with powder or more less coarse granular material, when with adhesive property product such as asphalt, there is a supplemental sealing 30 at the lobe fold end 16, 21, by the thermo plastic material.

Under the practice herein, while the end closure may be for the bottom of a tubular container, such may have the lobe infolds to radiating ribs 28 as inwardly projecting to converge spaced from the apices 13. Whether or not such be left as inwardly extending fins as major diametrical reinforcement, or be flattened out to be against the inner sides of the triangles 10, there is a non-score region of the lobe tips 16, 21, which may carry an adhesive 31. There is thereby developed a tight sealing in the handling of powder or granular material which may not have the transition stage of sealing as discussed for asphalt.

The snap locking for automatically holding the end closure is effected by having cylinder 32 (Fig. 1) of a diameter 33, which under the 13 $\frac{1}{2}$ " dimension hereinbefore taken as an example, may be with the score line sides 8, 9 of the triangles 10 in the range of 7". From this it follows, as the apices 13 are thrust inward to have the triangles 10 move toward a common plane therefor, the somewhat longer or hypotenuse distances at the perpendicular portions 16 snugly ride against each other in creating slight bulge corners 34 in developing the hexagon type of the regular polygon end closure. Because this final closing operation is desirably not taken after rigid setting of the contents, but prior thereto when there is some dimension accommodation characteristics left therewith, the contents, say of cooling asphalt, has its syrupy flow-in firmly to fill the corners 34 as radially reinforced by the lobe ribs 28. As the down thrusting of the points or apices 13 of the six triangles 10 is to an extent for the abutting thrusting between the lobe end arm portions 21 to ride to the straight portions 16, there is shorter radius approach to the lines 8, 9, and there is thus a sort of toggle quick lodging of the triangles in a common plane. Even rough handling tending to crumble hardened asphalt in the end corners has sifting therefrom almost totally eliminated.

From the foregoing it is to be noted that embodiment with special advantages ensue when the triangles 10 for the series total even, so that there may be alignment between score lines 8, 9 of adjoining triangles and the score lines 9, 8 of the adjoining diametrical opposite pair of triangles 10. There is thus achieved not only the diametrical thrusting but accompanying radial reinforcement for the approximately flat end. In some instances, the inward thrust of the apices 13 may be to such an extent as to leave the end dished inward slightly. This may occur when the thrust is sufficiently vigorous to take up approximately all, or at least more, of the end void than should the thrust be discontinued at the snap-lock approximately planar position. The score lines 8, 9 form a zigzag endless course from the drum body end score line 7 for the integral end

closure extension from the scoring connection 7. The lobe pairs 22, 23 comprise a second annular or endless series interfitting with the triangle endless series 10. At the closure, the lobe pairs 22, 23 bond as a two-ply radially extending rib. In the adoption of symmetrical polygon form, the respective triangles are isosceles, or have the score sides 8, 9 of equal length.

The completed and filled drum or container is rollable, may be stacked, sidewise or on end, and either end up. In adopting such general rough handling, there should be sufficient adhesion action between the contents and the container closure and body, or the incorporation of the adhesive 31. Accordingly here there is primarily a single service container which may be stored and shipped flat, while responsive to tubular set-up with integral self-locking and self-sealing radially reinforced end closure or end closures.

The isosceles triangles 10 in their blank extend beyond the cylindrical tubular body 4, 5 have the lines or sides 8, 9 in the range of 8% longer than the true radius for the drum, in thereby promoting the outward thrust for the corners 34 and the medial toggle.

What is claimed and it is desired to secure by Letters Patent is:

1. An open ended fiberboard drum and closure formed thereby by folding inwardly a portion of the container wall adjacent said opening, said portion being defined by a peripheral fold line, the upper edge of said drum defining said opening being scalloped to form a series of lobes, said portion including pairs of convergently inclined fold lines extending from said peripheral fold line and said inclined pairs of fold lines intersecting at points on said scalloped edge between adjacent pairs of adjacent lobes of said scallops, other fold lines alternating with said inclined pairs of fold lines extending at right angles to said peripheral fold line and terminating at points between said pairs of scallops, the lines forming the edges of said scallops extending from the point of intersection of said inclined fold lines being straight lines at right angles to adjacent inclined fold lines; and the lines forming the edges of said scallops extending from said right angle fold lines being curved lines, whereby when said portion is folded inwardly to form the closure, that portion forming the straight line of said scallops abut axially in said closure.

2. A collapsed cylindrical container comprising: a pair of flat sides connected along their opposite edges and having an end closure portion at one end of said sides, said closure portion having a scalloped outer edge and being separated from said sides by a fold line which also forms the base line of a plurality of adjacent isosceles triangle sections, said triangle sections being further defined by pairs of converging fold lines from the base line which pairs intersect in apices along said scalloped edge, there being between each apex a pair of lobes of said scalloped edge, the outer edges of said lobes connecting said apices comprising straight lines at right angles to adjacent converging fold lines and then curved inwardly to form the center recess of each lobe pair, and additional fold lines at right angles to said base line extending from adjacent base angles of said triangles to said recess between said pairs of lobes of said scalloped edge, whereby said closure portion forms at the end of a cylindrical container a flat closed end made up of said triangle sections with said right angle edges of said

lobes abutting each other axially of said container.
